DESIGN FOR A DRESS

Margaret Gaudiosi, New York, N. Y.

Application October 28, 1940, Serial No. 96,114

Term of patent 3½ years

To all whom it may concern:

Be it known that I, Margaret Gaudiosi, a citizen of the United States, residing at 27 West 96th St., New York city, in the county of New York and State of New York, have invented a new, original, and ornamental Design for a Dress, of which the following is a specification, reference being had to the accompanying drawing, forming part thereof.

Fig. 2 is a rear view of the same;

I claim:

The ornamental design for a dress, substantially as shown and described.

MARGARET GAUDIOSI.
